UNITED STATES PATENT OFFICE

1,952,211

DEVICE FOR THE SEPARATION OF MATTER
FROM LIQUIDSMaurice Loeb, Chicago, Ill., assignor to Frieda
Loeb, Chicago, Ill.

Application August 1, 1930, Serial No. 472,359

10 Claims. (Cl. 210—56)

The invention has to do with the recovery of matter such as fats and the like from liquids having a higher specific gravity than such matter, and particularly with the recovery of fats suspended in a liquid such as water.

Heretofore the devices for removing fats and the like from liquids have generally included a number of baffle plates or devices which serve a similar function. It has been found in the operation of devices of this character that the baffle plates cause a disturbance in the flow of the liquid, which is disadvantageous since separation is best accomplished of suspended matters when the liquid is disturbed as little as possible. Furthermore, in the devices referred to the substances to be separated pile up around the baffle plates and, in the case of fats, they form a hard, stiff crust which it is difficult to remove and after a period of operation the device does not function properly. Furthermore, the prior art devices have made no provision for the self-skimming of the matter to be removed. This has been done generally by hand. Such devices require practically constant attention since the skimming must be performed at regular intervals; otherwise in the case of fats and similar substances the fats will become hard, the device clogged up, and in addition the substance being recovered may become putrid or rancid and lose its value.

The primary object of the present invention is to provide a method and device in which the skimming operation is performed automatically.

A further object of the invention is to eliminate the piling up of the fats in the separation chamber and elsewhere and to insure a constant removal of the separated material as it separates from the liquid containing the same.

Still another object of the invention is the provision of means whereby the separated material may be conveniently removed.

Other objects and advantages of the invention will be obvious to those skilled in the art upon understanding the preferred embodiments thereof herein disclosed. It is to be understood that the preferred device, hereinafter disclosed, is for purposes of exemplification only since obviously changes may be made therein without departing from the true spirit and scope of the invention as defined by the appended claims.

Referring to the annexed drawing:

Fig. 1 is a view in cross section of a device embodying the invention;

Fig. 2 is a top plan view of the device;

Fig. 3 is a view in cross section taken on the line 3—3 of Fig. 1;

Fig. 4 is a detailed cross sectional view taken on the line 4—4 of Fig. 2; and

Fig. 5 is a fragmentary detailed view taken on the line 5—5 of Fig. 4 showing a portion of the means for operating the skimming mechanism.

The device includes a separation chamber indicated in the drawing by the reference numeral 11, at one end of which the matter-containing liquid is introduced through the pipe 12 which is suitably secured to the end wall of the chamber. The bottom of the separation chamber 11 is inclined toward the outlet and the lower portions of the side walls converge inwardly at an increasing angle as they approach the outlet end, so that a channel portion is formed at the bottom of the separation chamber. The shallow end 13 of the chamber is directly below the pipe 12 and the deep end 14 is located at the outlet end of the chamber. The bottom portion of the chamber at the outlet end is relatively narrow.

Affixed to the end of the pipe 12 and to cause the introduced liquid to flow toward the bottom of the chamber is provided a fitting 15. This fitting projects outwardly and downwardly from the pipe as indicated in Figs. 1 and 2 and has, at the center of the inner front wall thereof, a V-shaped member 16 which divides the flow and causes a portion thereof to be distributed to the right and another portion to the left of said separating chamber.

The outlet end of the chamber is formed by an inclined wall 17 which is spaced from the narrow bottom 14 of the separation chamber. The outgoing liquid passes through the channeled bottom of the separation chamber under the wall 17 and thence through the passage 17a between the wall 17 and the wall 18 to a discharge conduit or pipe 19 which is located in the wall 18 approximately on the level with the inlet pipe 12. The bottom of the wall 17 is inclined toward the wall 18 so as to give a Venturi effect thus increasing the speed of the outgoing liquid as it passes under the wall 17 and into the passage 17a.

A housing 20 attached to the wall 18 is provided in which is mounted containers 21 that receive the skimmed off separated matter, as hereinafter described. Bail members 21a are attached to the containers to facilitate handling thereof. The top of the housing 20, which is indicated by the reference numeral 22, is removable therefrom or is hinged thereto so that it may be opened as shown in the drawing, hinges being provided at the point 23 and a locking device at the point 24.

It will be noted in the drawing that the inlet

end of the chamber 11 is rounded at the corners 25 and 26 as shown in Fig. 2. The purpose in rounding the chamber instead of providing square corners is to prohibit the formation of eddy currents and dead spots.

The skimming mechanism includes a plurality of skimming members or troughs, two being shown in the drawing and indicated by the reference numerals 27 and 28 respectively, which are provided with means for adjusting the height thereof. The skimming members may be of any desired shape although preferably somewhat narrower and deeper at their discharge ends. The tops of the troughs are so constructed as to be level and at approximately the top of the liquid in the separation chamber. The troughs shown in the drawing are provided with rounded ends 29 which conform to the shape of the separation chamber and the bottoms 30 thereof incline 20 at a sharp pitch toward the outlet end of the separation chamber. The side walls of the skimming member 31 converge toward the outlet end. Obviously if it were desirable the skimming members might be made a part of the side walls of the chamber.

The skimming members are supported at the inlet end of the chamber by means of a bar 32 which is secured to the side walls of the chamber and passes beneath the skimming members. The height of the bar 32 in the chamber and consequently the height of one end of the skimming members is adjustable. The means for adjusting the height of said bar comprises vertical slots 33 through which a bolt or screw 34 passes and screw threads into the side walls of the chamber. By releasing the screw-threaded member 34 the bar 32 may be raised or lowered and then firmly held in place by tightening said screw-threaded member. It is apparent that any means for adjusting the height of the skimming members may be utilized and in some installations no adjusting means need be provided to obtain satisfactory results.

Means are provided at the outlet end of the skimming members for conducting the grease therefrom, said means comprising a pipe or conduit 36 which is screw-threaded into the outlet end of the skimming member and which passes through the walls 17 and 18. Adjustment of the height of the outlet end of the skimming member is accomplished, as shown in Figs. 4 and 5, by means of the provision of an eccentric plug 36 which is screw-threaded into or fits tightly within a housing or passage 37 which is formed between the walls 17 and 18. A handle member 38 is attached to the eccentric plug 37 and the grease outlet pipe 35 is mounted off center in said plug. Obviously, by rotating the handle member 38 the plug 36 is rotated and the pipe 35, being mounted off center therein, is raised or lowered thus raising or lowering the outlet end of the skimming members. Attached to the pipe 35 is a flexible extension pipe 39 which is adapted to extend over the top of the grease container 21. To permit removal of the grease containers 21 from the housing 20, the flexible extension pipe 39 is bent upward so that the top thereof is above the top of its associated skimming trough, thus stemming the flow of the recovered material and providing clearance for the removal of the containers 21.

Automatic means are provided for flexing the extension pipe 39, which means includes a chain or wire 40 which is rotatably connected to the pipe 39 at one end and to the cover 22 at the other

end, so that when the cover 22 is elevated the free end of the flexible pipe 39 is also elevated and, conversely, when the cover 22 is lowered the pipe 39 drops back into position.

The cover 22 has associated with it a spring 41 that is connected to the cover through an angle iron 42 secured to the under side of the cover at the hinged end thereof and at its other end to the outer wall 20 of the device. Thus when the locking bolt 24 is released, the cover will be thrown open under the action of the spring 41, the free end of the flexible pipe 39 raised, the flow of the separated material stemmed, and clearance is afforded for raising the containers 21 out of the device for emptying.

In the operation of the device, the liquid-containing fats or similar matter is introduced through the pipe 12 and directed downwardly by the coupling 15. Due to the shape of the coupling 15 the flow is spread out toward the sides of the separation chamber and a current progresses across the bottom of the chamber to the outlet end 14 thereof. The central and top portions of the chamber are quiescent so that as the fat separates out it gravitates to the quiescent surface of the liquid at the top of the chamber. The current or movement along the bottom of the chamber is increased as it passes under the wall 17 due to the Venturi effect resulting from the inclined relationship of the wall 17 to the wall 18. The fat free liquid then is conducted out of the apparatus through the discharge conduit 19.

The liquid being fed into the apparatus generally contains in addition to the substances to be separated, some other suspended matters which, having a specific gravity greater than that of the liquid, settle to the bottom and are carried along by the flow to the bottom end 14 of the chamber where it would normally tend to collect but due to the increased speed of the liquid under the wall 17 it is agitated and again suspended and carried up and out of the discharge conduit 19.

The separated material floating on the top of the quiescent liquid of the separation chamber 120 is drained off through the separating troughs 27 and 28 and, due to the step incline of the bottom of these troughs, gravitates to the discharge outlet thereof, passes through the conduit 35 and is emptied into the tanks 21.

By properly adjusting the height of the skimming troughs to compensate for surging very little liquid other than the separated material will be introduced therein and the material in the tanks 21 will be practically all separated material, thus the capacity of these tanks is utilized most effectively.

What I claim is

1. A device of the class described comprising a separation chamber, means for introducing liquid into said chamber, means for conducting liquid from said chamber, skimming means positioned at the liquid level of said chamber for continuously drawing off the separated material, a second chamber, a container mounted in said second chamber to receive said separated material, and means for stopping the flow from said skimming means upon opening said second chamber.

2. A device of the class described comprising a separation chamber, said separation chamber being progressively deeper from the inlet end thereof to the outlet end thereof and the bottom portion of said chamber being narrower than the top portion, means for introducing liquid

- into said chamber, means for discharging liquid from said chamber, skimming means positioned at the top of said chamber, a discharge outlet from said skimming means, a second chamber 5 having a door therein, a container for receiving the skimmed off material from said discharge outlet mounted in said second chamber, and means for stopping the flow of liquid into said container upon the opening of the door of said 10 second chamber.
3. A device of the class described comprising a separation chamber, skimming means positioned at the top of said chamber, means for vertically adjusting said skimming means, said 15 adjusting means including an eccentric mounted in the walls of said chamber and operably associated with said skimming means, and a discharge conduit connected to said skimming means and passing through said eccentric.
- 20 4. A device of the class described comprising a separation chamber, a storage chamber positioned at one side of said separation chamber, means for continuously skimming the liquid in said separation chamber and conducting the 25 skimmed off material into said storage chamber, and means for stemming the flow into said storage chamber upon opening of the same.
5. A device of the class described comprising a separation chamber, the side walls of the 30 separation chamber being rounded at the inlet end thereof and shallower at the inlet end than at the outlet end, the bottom of said separation chamber converging toward the outlet end, means for conducting liquid from the outlet end of the 35 chamber at the bottom thereof, means for introducing liquid into said chamber at the inlet end and directing the flow of liquid downwardly and toward the sides of said chamber, and means for continuously skimming the liquid positioned at 40 the top of said chamber.
6. A device of the class described comprising a separation chamber, a storage chamber positioned at one side of said separation chamber, containers adapted to be positioned within said 45 storage chamber, means for continuously skimming the liquid in said separation chamber, a flexible conduit connected to said last mentioned means and projecting into said storage chamber, the end thereof being above said containers, a cover for said storage chamber, means connecting said flexible conduit to said cover so that when said cover is raised the free end of said flexible conduit will be raised.
- 50 7. A device of the class described comprising a separation chamber, a storage chamber positioned at one side of said separation chamber, means for continuously skimming the liquid in said separation chamber, a flexible conduit for conducting the skimmed off material into said 55 60
- storage chamber, a cover hinged to said storage chamber, resilient means associated with said cover for opening the same, means connecting said cover with said flexible conduit so that when said cover is opened the free end of said conduit will be raised.
8. In a device of the class described, comprising a separation chamber, the bottom portion of said chamber sloping inwardly from the side walls and progressively narrowing from the intake end toward the exhaust end, means for introducing liquid into said separation chamber and directing the flow toward the bottom thereof, means for conducting liquid out of said chamber and upwardly, said means being positioned at the narrowest point in the bottom of said chamber to provide a relatively rapid flow along the bottom of said chamber and a substantially quiescent body of liquid at the top of said chamber.
9. In a device of the class described, comprising a separation chamber, the bottom portion of said chamber sloping inwardly from the side walls and progressively narrowing from the intake end toward the exhaust end, means for introducing liquid into said separation chamber and directing the flow toward the bottom, means for conveying liquid out of the bottom of said chamber and upwardly, said means being positioned at the narrowest point in the bottom of said chamber to provide a relatively rapid rate of flow along the bottom of said chamber and a substantial quiescent body of liquid at the top of said chamber, and means positioned at the liquid level of the heavier liquid in said chamber for skimming off the lighter liquid from said chamber.
10. In a device of the class described, comprising a separation chamber, the bottom portion of said chamber sloping inwardly from the side walls and progressively narrowing from the intake end toward the exhaust end, means for introducing liquid into said separation chamber and directing the flow towards the bottom, means for conveying liquid out of the bottom of said chamber and upwardly, said means being positioned at the narrowest point in the bottom of said chamber to provide a relatively rapid rate of flow along the bottom of said chamber and a substantial quiescent body of liquid at the top of said chamber, means positioned at the liquid level of the heavier liquid in said chamber for skimming off the lighter liquid from said chamber.
